tion, Lynn, Mass., a corporation of Massachu-
sets

Application October 7, 1930. Serial No. 486,957

20 Claims. (Cl. 242—3)

This invention relates to winding machines and more particularly to machines for winding spheroids, such, for example, as golf balls, the body of which comprises a center or nucleus on which there is wound a body of rubber or other thread or filament. One of the objects of the invention is to provide a machine which may be operated at a high speed and with a high rate of output without kinkage, chafing or breakage of the thread and so arranged as to avoid piling up of the wound threads in groups or excessive thickness, but to secure automatically a desirable distribution of the wound threads and produce a wound ball of substantially spheroidal shape.

15 This and other objects of the invention will be best understood by the following description when taken in connection with the accompanying illustration of one specific embodiment thereof, while its scope will be more particularly pointed out in the appended claims.

20 In the drawings:—

Fig. 1 is a front elevation of a machine embodying one form of the invention;

Fig. 2 is a side elevation of the machine shown in Fig. 1;

Fig. 3 is a central, sectional elevation taken lengthwise the journal axis of the bearing roller and showing the relation of the latter to the underlying grooved rollers;

30 Fig. 4 is a view similar to Fig. 3 showing a modified form of bearing roller;

Fig. 5 is a sectional elevation taken transversely the grooved rollers and showing a bearing roller journaled in a movable supporting arm; and

35 Fig. 6 is a plan view of the bearing roller support shown in Fig. 5.

Referring to the drawings and to the illustrative embodiment of the invention therein disclosed, the winding machine is provided with the base 11 in which there are journaled in suitable bearings parallel spindles 13, the ends of which protrude from the front of the machine and are provided each with a roller 15 fixedly secured thereto, to be driven thereby. These rollers are 45 slightly separated, as shown in Fig. 1, and are preferably grooved so that a spheroidal body, such as indicated at 17 in the drawings, to be wound may be seated in the space between and above the rollers and rest upon the grooved surfaces thereof.

50 In the illustrative embodiment of the invention (as indicated in Figs. 2 and 3) the groove in each roller is of a generally broad V formation, so that viewed sidewise the roller has the appearance of two truncated cones joined by their smaller faces.

55 Preferably, though not necessarily, one or both

grooves are so shaped, as by inclining the side 19 (see Fig. 3) at a slightly sharper angle than the side 21, that a true spheroid when positioned on the rollers, while resting at two points on both opposite inclined face of each roller, contacts on one inclined face with a circumferential element of slightly greater diameter than the circumferential element with which the spheroid contacts on the same roller. Accordingly, when the two rollers are driven in the same direction (represented by the arrows in Fig. 1), there is not only imparted to the spheroid a rapid winding movement about an axis parallel to the axes of the two rollers, but there is also imparted to the spheroid a tendency more or less marked to turn slowly about an axis perpendicular to the plane defined by the axes of the two rollers.

Any suitable means may be employed for imparting a high speed rotation to the rollers 15, but herein the spindle of each roller extends from the back of the machine base 11 and is provided with a pulley 23 having a belt connection 25 to an underlying pulley 27 on the shaft 29 of the electric motor 31. Each roller is driven by the described mechanism without longitudinal reciprocator or mechanically controlled movement other than that of simple rotation, it being thereby possible to impart to the spheroidal body supported by the rollers an unusually high rotative winding movement.

During the winding of the spheroid, the rubber or other thread 33 employed is fed to the spheroid through the slotted eye of a guide 35, the latter herein being conveniently carried by a bracket 37 secured to the side of the machine, the thread passing from the guide over the adjoining roller at the bottom of the groove thereof and about the under side of the spheroid 17. The guide bracket is fastened to the base of the machine by a screw passing through a slot in the side of the guide so as to permit adjustment of the latter to vary the angle at which the thread may be fed to the machine. The thread is supplied from a spool or other source of supply (not herein shown) and is preferably fed to the guide under tension, which may be provided either manually or by automatic tensioning devices (not herein shown).

During the winding operation, the spheroid is kept in bearing or seating contact with the rollers by an oppositely positioned bearing member 39, herein in the form of a roller, which bears upon the opposite, and herein top, surface of the spheroid as it is being wound. The bearing member is herein journaled in the head 41 fixedly

secured to the bottom of the plunger rod 43, the latter slidably mounted in the guiding bracket 45 of the frame so as to be capable of a vertical movement of a suitable range. The plunger 6 above the bracket 45 is provided with a rearwardly extending arm 47, and above the arm there is secured to the plunger the weight 49 to provide the necessary bearing pressure for the roller against the spheroid, this pressure being supplemented by that of the coiled spring 51, the lower end of which abuts against the arm 47 and the upper end against a pin 53 carried by the upper end of the vertical rod 55, the lower end of which is fixed in the machine frame. The 10 arm 47 is slidably guided on the fixed rod 55.

When the core or nucleus to be wound is inserted in the machine, or when the wound core is removed therefrom, the plunger with the bearing member is raised by means of the lever 57, 20 one arm of which bears against the under side of the weight 49, the lever being pivoted at 59 on the machine frame and its opposite end having the depending link 61 connected to the pivoted foot lever 63. When the foot lever 63 is 25 depressed the weight is lifted, raising the plunger and bearing member, permitting the insertion or withdrawal of the spheroid, at the same time compressing the spring 51. When the foot lever is released the plunger descends, being limited 30 in its downward movement by contact between the arm 47 and the top of the bracket 45. During the winding of the core the weight maintains a pressure on the bearing member which is steadied by the compression of the spring. In 35 the operation of the machine, as the winding proceeds the bearing member is gradually raised, raising the weight and slightly increasing the pressure effect of the spring 51 as the diameter of the ball increases and the pull of the thread 40 on the ball becomes greater.

To start and to automatically stop the winding operation, when the diameter of the wound core has reached a predetermined size, the following mechanism is provided. The motor is 45 stopped and started by means of a switch 65 of the ordinary two-push-button wall type positioned in a recess in the base 11 so that the starting button 67 and the stop button 69 project upwardly. Bearing against the stop button and 50 pressed into contact therewith by the spring 71 is a vertical switch closing plunger 73 which is slidably guided in a rearwardly projecting lug 75 on the machine frame, the upper projecting end of the plunger having a head 77 cooperatively related to the catch or detent 79 of a trip lever 81 pivoted at 83 on the upper end of an upstanding bracket 85 on the machine frame. The motor is started into operation by manually depressing the starting button 67 which simultaneously raises the stop button 69, lifting the 55 plunger 73 and causing the catch 79 to snap under the plunger head 77 and hold it in raised position. The trip lever 81 has a forwardly projecting arm 87 connected to the spring 89, so that the catch 79 yields laterally when the plunger is raised but snaps beneath the head thereof when the plunger is lifted to its upper position by the depression of the starting switch button 67.

70 As soon as the motor is started the winding operation starts, and as the diameter of the spheroid increases the bearing roller gradually rises until a core of the required diameter has been wound. When this point is reached the 75 tip of an adjusting screw 91 carried by the arm

47 on the plunger, which has already engaged the under side of a freely vertically movable pin 93, causes the upper end of that pin to come into contact with the bottom of an abutment 95 carried by the detent arm 87, causing the latter to lift and swing the catch back from beneath the plunger head 77. This instantly releases the plunger, causing it to move down against the stop button 69, depressing the stop button and stopping the motor instantly, the starting button 67 being moved reversely so as to leave it in its protruding position ready for starting the motor for the next winding operation. The abutment 95 is in the form of an adjustable screw so that it can be delicately and accurately adjusted to cause the stoppage of the motor and the cessation of further winding immediately when the diameter of the spheroid has reached the predetermined measure.

To avail of the high speed winding which can be obtained from the grooved rollers driven under a simple movement of rotation as described and which is a characteristic advantage of this type of machine, the bearing member must be carefully selected. The latter should perform not merely the function of holding the spheroid against the rollers 15, maintaining a steady pressure on the spheroid, but it should be so held as to permit its free and unimpeded winding movement, and the bearing member should so act as to spread or tend to spread the successive windings and prevent excessive piling up of the threads in one particular zone. If, under any conditions of use, there is substantial resistance offered by the bearing member to the winding movement of the spheroid, the thread will tend to break, chafe or kink, and if the bearing member tends to hold the spheroid so that for any substantial interval it continues to wind the threads while rotating about the same axis, the threads will accumulate in groups giving an unevenly or imperfectly wound core. I have found that these two functions of the bearing are combined by constructing it in the form of a roller journaled to rotate in anti-friction bearings about an established axis, whether or not it may have a movement in addition to its movement about such established axis, and further by so relating it to its point of contact on the spheroid that it tends at the same time to prevent the piling up of successive windings.

In the form of the invention illustrated in Fig. 3, the bearing member is in the form of the roller 39 which forms the outside race of a ball bearing, the balls of which are shown at 97, and the inner ball race at 99. The inner race is fixedly secured on a journaling member comprising the stud 101 which is screwed into the head 41. The exterior bearing surface of the roller 39 is preferably convex and is thus mounted for frictionless, unimpeded rotation about the axis established by the stud 101. The latter herein is inclined at a slight angle to the seating or supporting plane of the spheroid, which is determined by its points of contact with the grooved rollers and would here be approximately parallel to the plane defined by the axes of the two rollers 15, so that the roller bears against the spheroid at a slight angle, the plane of rotation of the roller being inclined to an axis of the spheroid passing through the point of contact with the roller.

The point of contact between the spheroid and the roller 39 is here shown as occurring in a vertical plane approximately intersecting the center of the spheroid, but this point of contact may

be adjusted somewhat to one side or the other of that point by means of the screws 103 which secure the head to the flange 105 of a connecting piece employed to fasten the head to the plunger, 5 the screws passing through slots in the flange.

The exact movements of the spheroid which take place during the winding operation are difficult of precise description since they are compounded with movements resulting from variations in the angle at which the thread is fed to the spheroid and with movements which result from more or less irregular contact between the faces of the rollers 15 and rapidly changing surface of the spheroid, and from other conditions 10 not susceptible of exact analysis, due to the high speed at which the machine is operated. In general, however, the spheroid, besides turning rapidly about a horizontal axis parallel to the axes of the rolls and serving to wind on the rubber thread, also tends to be gradually turned about an axis perpendicular to the plane defined by the axes of the rolls spreading successive windings of the thread, and to this there is added an action of the bearing roller when applied as illustrated in the drawings, tending to further conform the winding to a true spheroidal shape. This appears to be due to the fact that with the described movement of the spheroid under the influence of the rollers 15, each successive convolution of the thread tends to approach the bearing roll at a slight angle or off-set so that the roll exerts a slight lateral thrust against the spheroid, not only preventing any piling up of the threads in that zone, but producing in the aggregate a gradual shifting of the spheroid about an axis transverse to the rollers but parallel to the plane defined by their axes, thereby securing a movement of the spheroid which is compounded of movements in all three planes of space. 40 Whether this is an accurate or exact description of the resultant movement of the spheroid, it has been found that the effect of the roller 39 is to permit the rolls to be driven at high speed, such as 2500 to 3500 R. P. M. or more, without 45 kinking or breaking the thread and at the same time avoiding any marked piling up or chafing of the threads or tendency to ellipsoidal winding and providing a resultant body of satisfactory spheroidal shape.

50 At high winding speeds, the bearing roller alone may be relied upon to impart the necessary movements to the spheroid other than the winding movement referred to, and which here takes place about a horizontal axis, and the rollers 15 in that case may be formed with either V or concave shaped grooves without any attempt to shape them so as to afford points of contact with the spheroid on circumferential elements of different diameter on opposite sides of the plane on which winding takes place.

In the operation of the machine, the operative raises the plunger and bearing member by depressing the foot lever 63 and inserts between the rolls the center or nucleus to be wound, having attached thereto an end of the rubber thread leading from the source of supply. The bearing roller is then allowed to descend against the top of the center by releasing the foot lever and the starting switch button 67 is depressed which instantly starts the motor and initiates the rapid winding movement of the center. The depression of the starting button 67 raises the stop button 69 and the plunger 73, the plunger head being thereupon caught and held beneath the catch 79. 75 The adjusting screws 91 and 95 having been pre-

viously set with reference to the exact diameter of core desired to be wound, as soon as this diameter has been reached, the adjusting screw 91 is moved by the pin 93, throwing the trip lever 81, releasing the plunger 73, depressing the stop button and stopping the motor. At the same time, the starting button is raised, leaving the machine in condition to wind the next core as soon as the wound core has been withdrawn from the machine. 80

In Fig. 4 there is shown a modified form of bearing member 107, which comprises a roller having a bearing face of cylindrical shape and mounted on ball bearings to turn about an established axis provided by the stud 109, the latter, 90 however, being herein parallel to the rollers 15 and to the plane defined by their axes. Parallel sets of balls are herein provided and the roller 107, which forms in effect the outer ball race, has an inner concave spheroidal face which contacts 95 with the balls so that, in addition to the rolling movement about the axis of the stud 109, the roller is capable within certain limits of a free rocking or oscillating movement about the balls at right angles to the plane of its rolling movement and about a center lying in the axis of the stud 109. This tends to produce a movement of the spheroid which appears similar in kind to that effected by the bearing roller 39.

A similar effect may be produced by mounting 105 a bearing roller on a support such that the stud or other support on which it rotates is capable of a lateral or other movement, giving the roller a movement which, as in the case of the roller 107, is compounded of its rolling movement and another movement, herein the movement of its support. Such a construction is shown in Figs. 5 and 6.

In this form of the invention the bearing roller 111, having an outer cylindrical bearing surface, 115 is mounted on the stud 113 to turn on ball bearings similar to the bearings provided for the roller 39 (Fig. 3), the stud providing a horizontal axis of rotation. The stud 113, however, is carried by the arm 115, the opposite end 120 of which is pivoted to turn about a vertical axis at a point removed and relatively from the bearing roller through means of the pivot pins 117 carried by the bifurcated end of the bracket arm 119, the opposite end of which is clamped to the 125 lower end of the plunger 43. The proportions and relation of the bracket arm 119 and swinging arm 115 are such that when the bracket is clamped on the plunger the arm 115 lies in a generally parallel direction below the bracket arm 130 and above and across the rollers 15, but is capable of swinging freely to one side or the other so that the roller moves bodily across the contacting surface of the spheroid, the point of contact between the roller and the spheroid moving 135 along an arc intersecting the axis of the plunger and that of the spheroid. A slight swinging movement of the roller is all that is required, and to limit this movement and prevent the roller from moving so far that the spheroid is 140 no longer effectively held in bearing relation to the rollers 15, a limiting device is provided in the form of a lug 121 mounted on the arm 115 and adapted to engage with the adjacent walls of the bifurcated bracket arm when the lateral 145 movement of the arm 115 and roller 111 becomes more than necessary to control the desired winding movement of the ball.

While I have herein shown and described for the purpose of illustration one specific embodiment

ment of the invention and one or more modifications thereof, it is to be understood that extensive changes and deviations may be made from the forms in which it is herein embodied and 5 from the type of winding machine to which it is applied, all without departing from the spirit of the invention.

Claims:

1. A winding machine for winding spheroids 10 having a plurality of grooved rollers presenting a seat for a spheroid, means for driving said rollers to impart a winding movement to the spheroid, a bearing member for the opposite face of the spheroid comprising a roller, a supporting head 15 movable toward and from the spheroid, means for yieldably pressing the head toward the spheroid, a journaling member in the head establishing a fixed axis of rotation for the roller, and anti-friction bearings between the journaling member 20 and the roller, said roller being adapted to rotate in a plane inclined to the seating plane of the spheroid.
2. A winding machine for winding spheroids 25 having grooved rollers presenting a seat for the spheroid, means to drive said rollers with a simple movement of rotation, a bearing member for the opposite face of the spheroid comprising a freely rotatable roller yieldably pressed against the opposite face of the spheroid, and anti-friction 30 bearings for said roller, the plane of rotation of said roller being inclined with relation to an axis of the spheroid passing through the point of contact with the roller.
3. A winding machine having a pair of grooved 35 rollers forming a seat for a spheroid, means for driving said rollers, and a bearing member yieldably pressed against the opposite face of the spheroid and comprising a roller having a convex bearing face mounted to turn on anti-friction 40 bearings about an axis inclined to the seating plane of the spheroid.
4. A winding machine for winding spheroids 45 having rollers presenting a seat for the spheroid, means for driving said rollers to impart thereto a simple movement of rotation, and a bearing member yieldably pressed against the opposite face of the spheroid and comprising a roller mounted to turn about an axis inclined to the seating plane of the spheroid.
5. A winding machine for winding spheroids 50 having a pair of grooved rollers presenting a seat for a spheroid, means for driving said rollers, and a bearing member yieldably pressed against the opposite face of the spheroid and comprising a roller mounted to turn about an established journaling axis, said roller also being mounted for an oscillating movement with relation to its established axis of rotation.
6. A winding machine for winding spheroids 55 having a plurality of rollers presenting a seat for a spheroid, means for driving said rollers, a bearing member yieldably pressed against the opposite face of the spheroid comprising a roller, a journal for the roller, and an anti-friction bearing 60 between the journal and the roller on which the roller is adapted to have a rocking movement.
7. A winding machine having grooved rollers 65 presenting a seat for a spheroid, means for driving said rollers, and an anti-friction bearing member yieldably pressed against the opposite face of the spheroid and movable bodily across the contacting surface thereof.
8. A winding machine for winding spheroids 70 having a pair of adjacent driving rollers on which the spheroid rests, one of said rollers presenting

points of seating contact for the spheroid on opposite sides of the plane in which winding takes place and at circumferential elements in said roller of different diameter, said rollers being adapted to turn the spheroid both about an axis parallel to the axes of the rollers and about an axis perpendicular to the plane defined by the axes of the rollers, means for imparting to said rollers a simple movement of rotation, and a bearing member rotatable about an established axis and yieldably pressed against opposite faces of the spheroid at a point where successive windings take place, said bearing member having a convex rim for meeting the oncoming windings and exerting a lateral thrust to shift the spheroid about an axis transverse to the axes of the rollers.

9. A winding machine for winding spheroids 80 having a pair of adjacent driving rollers on which the spheroid rests and adapted to turn the spheroid both about an axis parallel to the axes of the rollers and about an axis perpendicular to the plane defined by the axes of the rollers, means for imparting to said rollers a simple movement of rotation, and a bearing member rotatable about an established axis and yieldably pressed against opposite faces of the spheroid at a point where successive windings take place, said bearing member having a convex rim for meeting the oncoming windings and exerting a lateral thrust to shift the spheroid about an axis transverse to the axes of the rollers but parallel to a plane 85 defined by their axes.

10. A winding machine comprising means for supporting and rotating a spherical core about a predetermined axis to receive an elastic thread 90 and at the same time leaving the core free to be angularly displaced, means for delivering thread in a definite winding zone, and a roll with a convex rim, journaled to rotate about an axis extending at all times transversely to the winding zone, contacting with the core in the winding zone and tending automatically by reacting with the wound thread to displace the core as the diameter of the winding zone increases.

11. A winding machine comprising means for 100 rotating a spherical core about an axis disposed transversely to its winding plane to receive an elastic thread, and a roller with a transversely curved rim contacting with the core, the roller being confined to rotate with its rim in said plane 105 and reacting with the most recently delivered turns of thread to displace the core to one side or other from the point of contact.

12. A winding machine comprising parallel 110 rollers providing a plurality of spaced points of seating contact for maintaining a spherical core in an established position, means for driving at least one of said rollers with a rotational movement only to impart a high speed winding movement to said core about an axis parallel to the 115 axes of the rollers, means for delivering guided thread to said core to establish a definite winding zone, and means to shift the rotational axis of the core as the latter is rotated to preserve its spherical form, the same comprising a roller 120 having a convex rim journaled to rotate freely about a single established axis, said rim contacting with the core at substantially a single point and against the last wound thread in the winding zone, and subjecting the core to a substantially constant yielding pressure toward its seat thereby to react upon the most recent turns of wound threads and shift the rotational axis of the core.

13. A winding machine comprising means for 125

- seating a spherical core on one side at a plurality of points spaced about its surface, said means being movable to impart a high speed rotation to the core, means for delivering a guided thread 5 to the core to establish a definite winding zone, and means for detecting high points in the thread windings and shifting the rotational axis of the core, the same comprising a roller confined to rotate freely about a single axis, yieldably engaging the core at a single point in the winding zone on the opposite side from the supporting means, and subjecting the core to a substantially continuous pressure whereby it may react transversely to the winding zone to shift 10 the rotational axis of the core.
14. A winding machine comprising means for supporting and rotating a core to be wound of elastic thread, means for leading an elastic thread thereto in a definite winding zone, and a detector disk provided with a transverse journal 20 upon which it is arranged to turn freely, and having a convex rim arranged to run on the core at a point in said winding zone and to react with the most recently delivered turns of thread to 25 displace the core to one side or the other from the point of contact to maintain it in spherical form as wound.
15. A winding machine for winding spheroids having a plurality of rollers presenting a seat 30 for the spheroid, means for guiding winding thread to the spheroid, means for driving said rollers to turn said spheroid and wind the thread about the same, said rollers presenting a point of seating contact for said spheroid on opposite 35 sides of the plane in which the winding takes place and at circumferential elements in said rollers of different diameter, and a bearing roller journaled to rotate about an established axis and yieldably pressed against the opposite face of the 40 spheroid, said roller having a convex rim for meeting the oncoming windings of said spheroid and exerting a lateral thrust thereagainst to shift the spheroid about an axis transverse to the axes 45 of the rollers but parallel to a plane defined by their axes.
16. A winding machine having rollers presenting a seat for a spheroid and acting to turn the latter both about an axis parallel to the axes of the rollers and about an axis perpendicular to the plane defined by the axes of the rollers, means for driving said rollers to impart thereto a simple movement of rotation, and a bearing member yieldably pressed against the opposite 50 face of the spheroid and comprising a roller mounted to turn upon anti-friction bearings determining an established axis and having a convex bearing face.
17. A winding machine for winding spheroids having grooved rollers of different effective diameter arranged to provide a seat for the spheroid and adapted to turn the latter both about an axis parallel to the axes of the rollers and about an axis perpendicular to the plane defined by the axes of the rollers, means for driving said rollers with a simple movement of rotation, a bearing member yieldably pressed against the opposite face of the spheroid comprising a freely rotatable roller, an arm carrying said member, and a pivotal support for said arm laterally removed and remote from the roller to provide for a free movement of the bearing member bodily across the contacting surface of the spheroid.
18. A winding machine for winding a spherical body of elastic thread, having grooved rollers providing a winding seat, means for driving said rollers with a simple movement of rotation, an anti-friction bearing member yieldably pressed against the opposite face of the wound body, an arm carrying said member, and a support for the arm, said arm being movable on said support and providing for a movement of the bearing member bodily across the contacting surface of the wound body.
19. A winding machine for winding spheroids, having a pair of rollers presenting a seat for a spheroid, means for driving the rollers, a bearing roller yieldably pressed against the opposite face of the spheroid, a roller support in which it is journaled to rotate about an established axis, and means movably carrying said support to permit the movement of the roller bodily across the wound surface of the spheroid.
20. In a winding machine having a pair of rollers providing a seat for a spheroid and acting to turn the latter about an axis parallel to the axes of the rollers and to permit it to turn about an axis perpendicular to the plane defined by the axes of the rollers, means for driving said rollers, a roller mounted for rotation on anti-friction bearings about an axis established thereby and adapted to engage the opposite face of the spheroid, a transversely movable support for said bearings, and means for yieldably pressing the support toward the spheroid, said roller having a movement of rotation about the axis of its bearings and a movement varying the position of its contact across the face of the spheroid.

FRED W. BOMMER.
